DISAPPEARING STAIRWAY

Jon R. Craig, Columbus, Ga.

Application April 19, 1949, Serial No. 88,273

2 Claims. (Cl. 228—50)

1

This invention relates to disappearing stairways.

An object of the invention is the provision of a disappearing stairway which is employed as a means of access to an attic, said stairway being formed of a main section carrying a panel for closing an opening in the ceiling and one or more auxiliary sections slideable in snug relation on top of the main section when the stairway is stored in the attic above the opening in the ceiling, counter-balances or springs being employed for aiding in raising or lowering the stairway or for aiding in retaining the stairway stored over the ceiling opening.

A further object of the invention is the provision of a disappearing stairway in which a main section has one end hinged to a casing embracing an opening in a ceiling, the other end of said main section and an auxiliary section slideable on the main section being supported and controlled during raising and lowering of the main section by springs and arms with the arms rocking on fulcrums carried by the casing and with the springs pulling on the upper ends of the arms for counter-balancing the weight of the stairway.

The invention consists in the novel construction, arrangement and combinations of parts hereinafter more particularly described and claimed.

In the drawings:

Figure 1 is a view in perspective of a disappearing stairway shown in an operative position.

Figure 2 is an enlarged transverse vertical section through a side of the casing which embraces the opening in a ceiling disclosing the means for controlling the positions of supporting arms for the stairway.

Figure 3 is a fragmentary enlarged side view of the coordinated elements shown in Figure 2.

Figure 4 is a longitudinal vertical section through the casing applied to the ceiling opening showing the sections of the stairway folded upon each other and stored in an attic space.

Figure 5 is a fragmentary side view of the pivotal connections between a supporting arm and the main section of the stairway.

Figure 6 is a fragmentary end view of the construction illustrated in Figure 5.

Figure 7 shows more or less diagrammatically the movements of a supporting arm and controlling spring for the stairway.

Figure 8 is an enlarged fragmentary side view of the stairway showing a catch for holding a sliding section of the stairway in an operative position on the main section, and

2

Figure 9 is an enlarged fragmentary side view of the stairway showing a hook for retaining a sliding section in an inoperative position on a main section.

Referring more particularly to the drawings, 10 designates a frame or casing which is employed generally in connection with openings formed in the ceiling of a building to provide an entrance to an attic space. The opening is rectangular so that the frame will have parallel side walls 11 and 12 and parallel end walls 13 and 14.

A panel 15 for closing the elongated opening in the frame 10 has one end hinged to the lower edge of the end wall 13. A main section 16 of 15 the stairway is secured to the upper face of the panel and swings with said panel. The main section includes steps 17 and parallel supporting rails 18.

An auxiliary section 20 has spaced treads 21 20 connected together by spaced parallel supporting rails 22. Hooks 23 pivotally mounted on pins 24 carried by the inner faces of the rails 22 are adapted to connect with pins 25 projecting from the inner faces of the rails 18 of the section 16 25 adjacent the lower end thereof when the section 20 has been extended from the main section 16 (Figs. 1 and 8). The lower ends of the rails 22 are sheared off at an angle for neat engagement with the floor of a building. A hook 26 pivoted 30 on the outer face of one of the rails 22 of the section 20 is adapted to receive an adjacently disposed pin 25 for retaining the section 20 on the section 16 when the stairway is moved into storage (Fig. 9). If desired, two hooks 26 may be employed.

Two supporting arms 30 have the lower ends pivoted on bolts 31 secured to the rails 18 of the main section of the stairway and adjacent the lower or free ends of said rails (Fig. 6). A sleeve 32 is mounted in each bolt for spacing the lower ends of the arms from the outer faces of the rails 18. Inner edges 30a of the arms 30 are maintained in engagement with rollers 33 mounted on bolts 34 carried by the side walls 11 and 12 of the frame or casing 10 (Fig. 2). A washer 35 on the inner end of each bolt 34 aids in retaining the arms on the rollers.

Coil springs 40 have one end attached in any approved manner to the upper edge of the rear wall 13 of the frame 10. These springs extend forwardly and each has the other end secured to an adjacently disposed upper end of an arm 30. The springs tend at all times to pull on the upper ends of the arms and maintain said arms against 55 the rollers 33 which act as fulcrums for the arms

during the raising or lowering of the stairway. Stops 41 (Figs. 1 and 2) on the arms are adapted to contact the upper edges of the side walls 11 and 12 for limiting downward movement of said arms and likewise the main section 16 of the stairway. A rope or chain 42 has one end secured to the free end of the panel while the free end of said rope is adapted to be grasped by the operator for lowering the stairway.

The operation of my device is as follows: The 10 springs 40 are sufficiently strong to counter-balance approximately the weight W (Fig. 7) of the stairway so that it will not require any great amount of force to raise or lower the stairway. Furthermore the arms 30 acting as levers engage 15 the rollers 33 which act as fulcrums. It is to be borne in mind that the points on the lever-arms 30 where engaged by the fulcrums 33 vary as the stairway is raised or lowered so that the ratio between the long and short portions of the lever-arms at opposite sides of the fulcrums will vary. These changing ratios will aid materially in raising or lowering the stairway and for retaining the stairway in an inoperative position. In other words (Figures 4 and 7), the force applied 20 to the shorter portions of the lever-arms 30 by the pull on the rope 42 and the weight of the stairway is multiplied many times by the longer portion L of the lever arms to overcome the pull of the springs 40. In Figure 1 the shorter portions of the arms 30 are acted on by the springs 40 to overcome approximately the weight of the 25 stairway.

A pull on the rope 42 lowers the stairway in folded condition and the main section 16 has its free end supported by the stops 41 on the arms 30. The catch or hook 26 is released from the pin 25 to permit the auxiliary section to slide downwardly until the lower end rests upon the floor. The hooks 23 are then engaged on the pins 25. The stairway is ready for use. A reversal of the above described operations will place the stairway in condition for return to the storage space. The stops 41 may be adjusted along the arms 30 for properly positioning the free end of the main section 16.

What I claim:

1. A disappearing ladder for buildings comprising an open frame, a closure positioned within said frame and having one end mounted on one end of said frame for swinging movement into and out of closing relation therewith, a ladder positioned on the inner face of said closure and

fixedly secured thereto, means carried by said frame and operatively connected to said closure for normally positioning the latter in closing relation with respect to said frame, said means comprising a pair of supporting bars extending through said frame and swingingly supported intermediate their ends on the sides of said frame, one end of each of said bars being pivotally connected to said ladder adjacent to and spaced from the other end of said closure, and resilient means operatively connected to the other end of each of said bars and said one end of said frame.

2. A disappearing ladder for buildings comprising an open frame, a closure positioned within said open frame and having one end mounted on one end of said frame for swinging movement into and out of closing relation therewith, an extension ladder positioned on the inner face of said closure and fixedly secured to the latter, means carried by said frame and operatively connected to said closure for normally positioning the latter in closing relation with respect to said frame, said means comprising a pair of opposed rollers positioned within said frame adjacent the sides thereof and mounted thereon for rotation about a transverse axis, a pair of supporting bars extending through said frame intermediate the other end thereof and said rollers, means pivotally connecting said supporting arms to said ladder adjacent to and spaced from the other end of said closure, resilient means carried by said frame adjacent said one end thereof and operatively connected to the other end of each of said supporting bars for urging said arms into engagement with said rollers, and hand actuatable means carried by said closure for swinging the latter into and out of closing relation with said frame, said supporting bars swinging about said rollers acting as a fulcrum.
